UNITED STATES PATENT OFFICE.

HERMAN K. C. DE ANGUERA, OF WAKEFIELD, MASSACHUSETTS, ASSIGNOR
TO EDWARD DE ANGUERA, OF SAME PLACE.

VENTILATOR.

SPECIFICATION forming part of Letters Patent No. 624,888, dated May 9, 1899.

Application filed May 25, 1897. Renewed November 29, 1898. Serial No. 697,802. (No model.)

To all whom it may concern:

Be it known that I, HERMAN K. C. DE ANGUERA, of Wakefield, in the county of Middlesex and State of Massachusetts, have invented 55
5 certain new and useful Improvements in Ventilators; and I do hereby declare the following to be a full, clear, and exact description of the invention, such as will enable others skilled in the art to which it appertains to 10 make and use the same.

This invention relates to improvements in ventilators, and has more particular relation to ventilators adapted to be detachably applied to windows.

15 It will be understood from the following description and claim.

In the accompanying drawings, forming 20 part of this specification, Figure 1 represents a perspective view of the device embodying my invention in its open position with the curtain partly raised. Fig. 2 represents a rear elevation of the same. Fig. 3 represents an enlarged detail perspective view of the end guards provided with a plurality of adjusting- 25 apertures and a locking-pin, and Fig. 4 represents a central vertical section through my said improvement.

1 in the drawings represents the detaching-frame of my improvements; 2, the hinged 30 guard; 33, the rigid end guards, and 4^a the curtain. Said frame 1 is formed of two sections 4 and 5, respectively, hinged together, as at 6, by any suitable form of hinges. The small end section 5 is adapted to be opened in position when the device is applied to the window, so that the frame may extend fully into the respective beads formed on the opposite sides of the window and be thus held firmly in position. In order to hold the small frame 35 40 5 in alinement with the frame 4 when in use, the latter is provided with a turn-button 7, pivotally mounted thereon and adapted to engage said frame 5. The frame 4 is formed with an inlet-opening 8, covered by any suitable reticulated material 9 to prevent the entrance of flies or other insects. The respective rigid end guards 3, which are preferably 45 angular in formation, are rigidly secured to the inner face of the frame 1 at the respective 50 ends of the opening 8, while the guard 2 has its lower edge hinged to said frame 4 at the

bottom of the opening 8 and is adapted to extend up between the rigid ends 3 to a suitable distance above the upper edge of the opening 8. The object of this construction is to prevent the entrance of any direct draft into the room being ventilated. One of the said rigid end sections 3 is provided near its upper segmental edge with a plurality of spaced apertures 10, through which a suitable pin 11, 60 flexibly secured to said end by a cord or chain 12, may be passed to engage an aperture 13, formed in one end of the hinged guard. It will be observed from the foregoing that the said guard may be held firmly in any of its 65 adjusted positions either open or closed or at any intermediate point between these positions.

I preferably provide the outer ends of the frames 4 and 5 with binding-strips 14, whereby they will fit more snugly between the beads and the window-frame, and thus prevent any rattling of the attachment. The upper and lower edges of said frames 4 and 5 are respectively inclined, as shown in the drawings, so 75 that the frame when applied to a window will assume a slightly-inclined position, with its lower inclined edge resting flat upon the inclined sill and its upper edge squarely against the flat under side of the window-frame. By 80 this means the frame is jammed firmly between the respective beads of the window-frame, should it not be of a width equal to the groove of said beads, because of the inclined position assumed by it.

85 By means of my improvement all direct draft into a room is avoided and at the same time a perfect ventilator provided, which will prevent the entrance of all flies or other insects.

90 The device is very simple and cheap in construction and operation, but at the same time very effective, as it may be instantly applied or detached from a window and the quantity of air regulated by the adjustment of the hinged guard. By the peculiar construction of the hinged guard, whereby it is caused to extend considerably above the upper edge of the opening 8, all air entering through said opening 95 is forced upward in an inclined direction, and all direct draft into the room thus prevented. 100 When it is desired to fully open the ventilator,

the pin 11 is simply withdrawn and the hinged guard allowed to drop down against the frame 4.

For the benefit of consumptives and those troubled with pulmonary complaints I employ a curtain 4^a, made of cheese-cloth saturated with oil of pine-needles or other disinfectant and mounted upon an ordinary spring-roller 4^b, so that it may be drawn over the wire screen. The roller 4^b is mounted in the usual manner upon the inside of the guard, so as to lie between the screen and the movable lid. By the arrangement of this curtain the air may be medicated at will as it enters through the reticulated material.

Having thus described my invention, what I claim as new, and desire to secure by Letters Patent, is—

The combination with an apertured ventilator-frame, of triangular or sector-shaped

plates secured to the frame, one at each end of the aperture and forming end guards therefor, a guard-plate hinged to the frame below the aperture to swing in and out between the rigid end guards, means for engaging said hinged guard for locking it at any desired adjustment, a reticulated covering for the aperture in the frame, and a flexible, absorbent curtain adjustable on a roller journaled on the frame directly above the aperture therein, for the purpose and substantially as described.

In testimony whereof I have signed this specification in the presence of two subscribing witnesses.

HERMAN K. C. DE ANGUERA.
